CLAIM

The ornamental design for a bar set stand, as shown and described.

DESCRIPTION

FIG. 1 is a front, left, and top perspective view of a bar set stand, showing my design.

FIG. 2 is a rear, left, and bottom perspective view thereof.

FIG. 3 is a front, left, and top perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof; and,

FIG. 9 is a bottom plan view thereof.

The broken lines shown in the drawings are included for the purpose of illustrating portions of the bar set stand that form no part of the claimed design.

1 Claim, 9 Drawing Sheets
